HEATING PLANT

Walter Gustav Noack, Baden, and Claude Seippel, Ennetbaden, Switzerland, assignors to Aktiengesellschaft Brown, Boveri & Cie., Baden, Switzerland

Application December 2, 1937. Serial No. 177,792
In Germany December 2, 1936

14 Claims. (Cl. 263—19)

The present invention relates to a method and means for heating large amounts of gases or air to high temperature, more particularly to methods and means for producing hot blast for blast furnaces or the like.

5 The hitherto used hot blast plants, the so called Cowpers, which operate according to the regenerative principle are large, and expensive in first cost and upkeep. Since suitable high heat resisting material is available it has been proposed 10 to operate the hot blast producers according to the recuperative principle, i. e., instead of the intermittent operation, to continuously transfer heat in customary heat exchangers which are 15 made of highly heat resisting material, for example, special highly heat resisting steel.

Such plants are of advantage as long as the 20 temperature of the heated gas or air remains below 1300° F. There are many cases where temperatures above 1300° F. are required and, there, 25 heat exchangers operated according to the recuperative principle cannot be used because at such temperatures the strength of tube and housing material is not sufficient to carry the weight 30 of the apparatus and resist the internal pressures. In such cases the regenerative principle must be employed in which the heat exchange apparatus is not subjected to internal or external pressures and a reduction of the strength of 35 the construction materials caused by the increased temperatures is negligible. In order to overcome the great disadvantages connected with the regenerative principle, for example, large bulky and expensive equipment, heat losses, etc., 40 with the method and apparatus according to the present invention the rate of heat transfer is considerably increased by increasing pressure and velocity particularly of the heating gases and by making provisions for reducing the heating periods for the gases or air to be heated and accommodate these periods as much as possible to 45 the heating up or loading periods.

It is an object of the present invention to provide an air or gas heating plant for blast furnaces 50 or similar equipment which serves heating or reduction purposes in which plant the air or gas heater operates according to the regenerative principle and is heated by a heating medium of high pressure and high velocity. The pressure 55 of the heating medium according to the present invention is at least 3.56 lbs. per sq. inch and its velocity more than 130 feet per sec.; pressures of several atmospheres and velocities of 300 feet per sec. and over may be used. Due to these high pressures and temperatures a very high rate of

heat transfer is obtained so that heating up is accomplished very quickly and the dimensions of the apparatus can be small because particularly the heating gas passages can be held very small. The size of the plant is only a fraction of the 5 size of customary plants of same capacity.

According to the present invention a compressor is provided which is driven by means of a gas turbine which is operated by the heating gases used in the heating plant. No foreign power is 10 used for operating the compressor and no losses of heat or power are incurred by the arrangement according to the present invention. The operating efficiency of the plant according to the 15 present invention is high because the compression takes place practically without any loss and heat losses are reduced because of the much smaller dimensions of the plant.

According to the present invention also pressure and velocity of the gas or air to be heated 20 is greatly increased, whereby heat transfer and heat absorbing conditions are greatly increased.

Further and other objects of the present invention will be hereinafter set forth in the accompanying specification and claims and shown 25 in the drawings which, by way of illustration, show what we now consider to be a preferred embodiment of our invention.

• In the drawings:
Figure 1 is a diagrammatic lay-out of a plant 30 according to the present invention.

Figure 2 is a part sectional side elevational view of a plant according to the present invention showing parts of the plant in larger scale.

Figure 3 is a top view of a diagrammatic lay-out of a plant according to the present invention.

In the drawings 1 designates a consumer of heated gas or air, for example, a blast furnace, 2 and 2' are gas or air heaters, 3 is the compressor for the gas or air to be heated and 4 is the machine for driving the compressor 3. At the moment illustrated air or gas heater 2 is just being heated up, whereas heater 2' is discharging heat to the air or gas passing through it. Heater 2 is heated by the combustion of gas in air. The air and gas are compressed in the compressors 5 and 6 respectively. The heat produced by the combustion is transferred to the conventional heat absorbing bodies within the heater 2, whereby the high pressure at which combustion takes place and the high gas velocity resulting therefrom considerably reduce the time required for heating up and also the size of the heater. Not all heat produced by the combustion of the gases is absorbed in the heater; heating is interrupted 50

so that the high pressure gases retain enough heat for operating the gas turbine 7 which drives the gas and air compressors 5 and 6. The gases leaving the gas turbine 7 may still have considerable temperature and are therefore conducted through heat exchangers 2 and 2', the former heating the combustion air coming from compressor 5 and the latter heating the combustion gas coming from compressor 6.

10 All or part of the gases leaving the gas turbine 7 and the heat still contained in said gases may be used for preheating the gas or air to be heated in the heat exchangers 2 and 2'. For this purpose a conduit 12 may be provided which conducts gas from turbine 7 to heater 9.

15 For starting up, supplementary control and for supplying supplemental power when there is not sufficient power available from the turbine 7 to operate the compressors 5 and 6, an auxiliary motor 10 is provided which may be an electric motor, a steam engine or turbine, or an internal combustion motor.

20 The pressure, at which combustion takes place in the combustion chamber of the heaters 2 and 2' according to the present invention, considerably exceeds atmospheric pressure and is in between 3.7 lbs. per sq. inch and 44 lbs. per sq. inch. The gas and air velocities are also much higher than the usual velocities in the neighborhood of 6 feet per second and may, in plants according to the present invention, reach the value of 330 feet per sec. The power which is required for materializing these conditions is considerable but it is produced practically without additional expense by means of the gas turbine 7; all of the energy transformed in said turbine goes back to the combustion chambers of the heat exchanger 2, 2' in the form of heat.

25 The temperature of the gases entering turbine 40 7 is approximately 900 to 1100° F. The heat still in the gases exhausting from the gas turbine is partially used for preheating the fuel gas and combustion air and/or is used for preheating the gas or air to be heated in the heat exchangers 45 2, 2'.

30 Because of the density and increased velocity of the fuel gases the rate of heat transfer is much increased, whereby the heat transmitting surfaces of the heat exchanging bodies can be reduced and the time for heating up said bodies, i. e., for charging the heat exchanger is much reduced. According to the present invention the unloading periods, i. e., the periods during which the gas or air is heated in the heat exchangers 2 55 and 2' correspond to the loading periods and must therefore be considerably shorter than in conventional plants. The heat absorbing capacity of the gas or air to be heated must therefore be increased. This is done by increasing the 60 velocity of the gas or air passing through the heat exchangers 2, 2'. For producing the increased velocity an additional pressure drop must be available which is usually not available in conventional plants and an additional blower 65 11 supplementing blower 3 is provided. This blower may be driven by a separate motor or it may be interconnected with the charging unit 5, 6, 7, 10 and receive power from gas turbine 7 and motor 10. An installation of the latter type is 70 shown in the drawings. In order to save in the size of blower 11 and heater 9, if such heater is provided, not all, but only part of the gas or air is passed through blower 11 and heater 9. The other part flows directly from blower 3 through conduit 13 into the manifold 14 and

therefrom alternately through valves 15 or 16 into the heat exchanger 2 or 2'. Blower 11 and heater 9 by means of conduits 17, 18 and 19 are arranged in parallel to conduit 13. The gas or air heated in heat exchangers 2 or 2' is conducted through valves 20 and 21 respectively into conduit 22 and therefrom into the manifold 23 of the consumer of heated gas or air 1.

15 It is essential that the flow resistance of the heating gases and the gas or air to be heated is held as small as possible and limited to wall friction which causes heat transfer, and eddy currents, etc., are eliminated by proper design of the heat absorbing bodies and gas and air passages.

20 Usually a plurality, at least two, of heat exchangers are provided which are alternately charged and discharged or serve as standby. Such operation is controlled by the provision of suitable valves.

25 In the plant shown in the drawings and at the operating period illustrated the combustion air which is compressed in compressor 5 passes through conduit 24 into preheater 8 and therefrom through conduit 25, valve 26 which, at the 30 operating period illustrated, is open into heat exchanger 2. Conduit 28 which leads from conduit 25 into heat exchanger 2' is closed at this time by means of the closed valve 27. The fuel gas coming from compressor 6 is passed through conduit 29 into preheater 8 and therefrom through conduit 30 and valve 31 into heat exchanger 2 where it is burnt with the combustion air. Heat exchanger 2' is shut off from conduit 30 at the period illustrated by means of valve 32 35 in conduit 33. The hot gases, after having heated up the heat accumulating bodies in heat exchanger 2 leave said exchanger through valve 34 and are conducted through conduit 35 into the gas turbine 7. At the moment illustrated 40 valve 36 which controls the passage of the heating gases from heater 2' into conduit 35 is closed.

45 In order to properly mix the gas or air of increased pressure and/or temperature in conduit 19 with that in conduit 13, conduit 13 is connected to the throat of the Venturi tube 38; there the pressure built up in supplementary blower 11 is converted into velocity and reduced to the pressure of the gas or air in conduit 13.

50 Figures 2 and 3 of the drawings show further details of the plant illustrated in Fig. 1. They show a plant in which the exhaust gases from the gas turbine 7 are used in a recuperator 9 to preheat the air or gas which is delivered by the compressor 3. Fig. 3 also shows the conduits and valves which have been omitted from the plan shown in Fig. 2 in order not to complicate this figure unnecessarily. One of the heat exchangers (2) is shown with its upper part in section. This sectional view shows a combustion chamber 42 in 60 which the gas supplied by the compressor 5 and the air supplied by the compressor 6 are subjected to combustion under pressure. The gas enters for example at 43 and the air at 44. The air and gas are mixed by the distributor 45 and ignited in the burner 46. Due to combustion taking place under pressure the combustion chamber is very small and can be arranged in the upper part of the heat exchanger, whereby a very favourable construction is possible. The products of combustion first flow downwards because due to their high velocity and density their path of flow must be comparatively long whilst the cross-section of flow is small and therefore these gases are directed upwards at least once more and again 70 75

5 downwards before they pass from the lower part of the heat exchanger into the gas turbine. In Fig. 2 the heat exchanger 2' is just in the charging period. Conduit 17' and change-over valve 36 are opened to the gas turbine whilst change-over valve 34 is closed.

10 The upper part of the combustion chamber 42 includes an annular space 40 separated by a partition 49 which has narrow communicating openings in it. During the charging period this annular space is filled with inert gases and the 15 change-over valve 21 to the blast furnace is closed. During the discharging period this annular space in both heat exchangers serves as a receiver for the air or gas which passes through opening 48 (or 48') and the open valve 20 (or 21) to the furnace. The air or gas supply comes through conduit 41 and the change-over valves 15 or 16. Previously the air or gas passes 20 through the heater (recuperator) 9 which on account of the comparatively low temperature of the heating gas (below 750° F.) can be made of metal whilst the heat transferring and heat accumulating elements in the heat exchangers (2, 2'), at least those parts which are subjected 25 to the high gas temperatures, must be made of stone (ceramic material).

30 In order to obtain a high heat transfer during discharge and to be able to finish the discharging in about the same time as the charging, the air or gas is given a higher velocity of flow. A special blower 11 is provided for this purpose in case this additional pressure drop cannot be provided by the compressor 3.

35 The exhaust gases which serve to heat the heater (recuperator) 9 leave the heater through the flue 47.

40 The charging set is started by a special engine 10 which is generally a steam turbine but can also be an electric motor or a gas engine. This engine also assists the gas turbine 7 in case the power of the latter is inadequate to drive the compressor which is coupled with it.

45 The great advantage of this pressure boosting or increase in pressure and velocity of the heating gases in the Cowpers is that all the dimensions of the plant can be considerably reduced. Not only is there a saving in space but above all material and capital costs are smaller. The compactness of the plant enables air or gas producers and heaters to be installed in the immediate vicinity of the blast furnace so that conduits are saved and heating losses reduced.

50 The reduction in size achieved is obvious when one considers that when the combustion pressure in the combustion chamber of the heat exchanger is increased to 2 to 3 atmospheres absolute the loading of the combustion chamber (free heat in the combustion chamber), according to results obtained with pressure fired plants, can be ten to twenty times higher than with atmospheric combustion. Since the increased pressure also enables the velocity of the heating gases to be considerably increased (from ten to twenty times) the sectional area of the heating gas channels can be reduced to a fraction (about $\frac{1}{30}$ to $\frac{1}{50}$) of its former value. The most important result of the pressure charging is, however, the reduction in the quantity of heat accumulating material required. Due to the much increased heat transfer heating-up and discharging is greatly accelerated on condition that the usual brickwork is used, and the charging and discharging periods can therefore be considerably shortened so that 75 the change-over operations follow each other

more rapidly. The heat accumulating elements can be correspondingly reduced. It is, however, advisable to use good heat conducting brickwork, such as carborundum of which the conductivity is 15 times higher than that of chamotte. For all 5 parts exposed to lower temperatures (below 1850° F.) metal, for example molybdenum cast-iron can be used. The change-over valves are of the usual construction. Since the velocities and densities are much higher the dimensions of the 10 valves will, however, also be smaller so that their automatic operation is easier.

15 While we believe the above described embodiments of our invention to be preferred embodiments, we wish it to be understood that we do not desire to be limited to the exact details of the method, design and construction shown and described, for obvious modifications will occur to a person skilled in the art.

20 We claim:

1. The method of producing large quantities of 25 highly heated gas or air comprising the step of alternately burning combustion materials at high pressure in a heat accumulator and driving the gas or air to be heated at high pressure and velocity through said accumulator, and producing power with the products of combustion and using said power for producing the high combustion pressure in said heat accumulator.

30 2. The method of producing large quantities of highly heated gas or air comprising the step of alternately burning combustion materials at high pressure in a heat accumulator and driving the gas or air to be heated at high pressure and velocity through said accumulator, and producing power with the products of combustion and using 35 said power for producing the high combustion pressure in said heat accumulator and for producing the high pressure and velocity of the gases to be heated.

40 3. The method of producing large quantities of highly heated gas or air comprising the step of alternately burning combustion materials at high pressure in a heat accumulator and driving the gas or air to be heated at high pressure and 45 velocity through said accumulator, and producing power with the products of combustion and using said power for producing the high combustion pressure in said heat accumulator and for pre-heating the combustion materials with the heat 50 left in the products of combustion after having produced power.

45 4. The method of producing large quantities of highly heated gas or air comprising the step of alternately burning combustion materials at 55 high pressure in a heat accumulator and driving the gas or air to be heated at high pressure and velocity through said accumulator, and producing power with the products of combustion and using said power for producing the high combustion pressure in said heat accumulator and preheating the gas or air to be heated with the heat 60 left in the products of combustion after having produced power.

50 5. The method of producing large quantities of highly heated gas or air comprising the step of alternately burning combustion materials at high pressure in a heat accumulator and driving the gas or air to be heated at high pressure and 70 velocity through said accumulator, producing power with the products of combustion and using said power for producing the high combustion pressure in said heat accumulator, and preheating the combustion materials and the gas or air to be 75

- heated with the heat left in the products of combustion after having produced power.
6. The method of producing large quantities of highly heated gas or air comprising the step of periodically burning combustion materials at a pressure of at least 3.7 lbs. per sq. inch in a heat accumulator and driving the products of combustion through said accumulator at a speed of at least 130 feet per second and producing power with the products of combustion after they have left said accumulator and using said power for producing said high combustion pressure.
7. A heating plant for producing highly heated gas or air comprising a plurality of heat exchangers of the fuel burning and heat accumulating type, combustion material supply means periodically supplying combustion materials at high pressure to one and then to another of said heat exchangers, a gas turbine periodically connected for gas flow to that one of said heat exchangers which is supplied with heating materials and being adapted to be operated by the gaseous products of combustion emerging from said heat exchangers and being connected to and driving said combustion material supply means.
8. A heating plant for producing highly heated gas or air comprising a plurality of heat exchangers of the fuel burning and heat accumulating type, combustion material supply means periodically supplying combustion materials at high pressure to one and then to another of said heat exchangers, a gas turbine periodically connected for gas flow to that one of said heat exchangers which is supplied with heating materials and being adapted to be operated by the gaseous products of combustion emerging from said heat exchangers and being connected to and driving said combustion material supply means, a preheater interposed in the path of said combustion materials in between said supply means and said heat exchangers and being connected for gas flow with said gas turbine and adapted to be heated by gases exhausting from said turbine.
9. A heating plant for producing highly heated gas or air comprising a plurality of heat exchangers of the fuel burning and heat accumulating type, combustion material supply means periodically supplying combustion materials at high pressure to one and then to another of said heat exchangers, a gas turbine periodically connected for gas flow to that one of said heat exchangers which is supplied with heating materials and being adapted to be operated by the gaseous products of combustion emerging from said heat exchangers and being connected to and driving said combustion material supply means, air or gas supply means connected with said heat exchangers for periodically supplying air or gas to be heated to said heat exchangers and being also connected with and driven by said gas turbine.
10. A heating plant for producing highly heated gas or air comprising a plurality of heat exchangers of the fuel burning and heat accumulating type, combustion material supply means periodically supplying combustion materials at high pressure to one and then to another of said heat exchangers, a gas consumer periodically connected for gas flow to that one of said heat exchangers which is supplied with heating materials, a preheater interposed in the flow of the combustion materials to said heat exchanger and being connected for gas flow with said gas consumer and being heated with gaseous products of combustion after they have passed through said consumer.
11. A heating plant for producing highly heated gas or air comprising a plurality of heat exchangers of the fuel burning and heat accumulating type, combustion material supply means periodically supplying combustion materials at high pressure to one and then to another of said heat exchangers, a gas turbine periodically connected for gas flow to that one of said heat exchangers which is supplied with heating materials and being adapted to be operated by the gaseous products of combustion emerging from said heat exchangers and being connected to and driving said combustion material supply means, and an auxiliary motor also connected with and driving said combustion material supply means during the starting up period and when not sufficient products of combustion are available for operating said gas machine.
12. A heating plant for producing highly heated gas or air comprising in combination, a heat exchanger, a gaseous heating medium passed at high pressure and high velocity through said heat exchanger, a gas turbine connected for gas flow with said heat exchanger and being operated by gaseous heating medium coming from said heat exchanger, gas or air supply means connected with said heat exchanger and supplying gas or air to be heated to said exchanger, booster means arranged in the gas or air flow to said exchanger for increasing the pressure of said gas or air, said booster means being connected with and driven by said gas turbine.
13. A heating plant for producing highly heated gas or air comprising in combination, a heat exchanger, a gaseous heating medium passed at high pressure and high velocity through said heat exchanger, a gas turbine connected for gas flow with said heat exchanger and being operated by a gaseous heating medium coming from said heat exchanger, gas or air supply means including a gas or air conduit connected with said heat exchanger and supplying gas or air to be heated to said exchanger, booster means arranged in parallel with respect to the gas or air flow to said exchanger and through said conduit for increasing the pressure of said gas or air, said booster means being connected with and driven by said gas turbine.
14. A heating plant for producing highly heated gas or air comprising in combination, a heat exchanger, a gaseous heating medium passed at high pressure and high velocity through said heat exchanger, a gas turbine connected for gas flow with said heat exchanger and being operated by a gaseous heating medium coming from said heat exchanger, gas or air supply means including a gas or air conduit connected with said heat exchanger and supplying gas or air to be heated to said exchanger, booster means arranged in parallel with respect to the gas or air flow to said exchanger and through said conduit for increasing the pressure of said gas or air, said booster means being connected with and driven by said gas turbine, and a preheater arranged also in parallel with said conduit and in series with respect to the flow of gas or air and being connected for gas flow with said gas turbine and heated by gaseous medium exhausted by said turbine.
